UNITED STATES PATENT OFFICE.

HERMANN STELZNER, OF LUBECK, GERMANY, ASSIGNOR TO FIRM DRÄGERWERK,
HEINR. & BERNH. DRÄGER, OF LUBECK, GERMANY.

CONNECTING RING FOR THE BELT OF BREATHING APPLIANCES.

Application filed June 7, 1928, Serial No. 283,704, and in Germany September 2, 1927.

In applying breathing appliances, such as breathing masks, there is the inconvenience that some kind of belt or band is to be attached at a place which is not visible to the 5 wearer. Generally in such cases the connection is made in this way that a ring or link is placed on a hook of the appliance. Though such connection can be carried out comparatively easy yet there is the difficulty that the 10 link frequently slips away from the grip of the fingers. This is particularly the case when it is a question of a nape ring of masks or the like.

To avoid this inconvenience, according to 15 the present invention the link or ring is roughened (serrated or knurled) on the outside, so as to facilitate the applying of the connecting pieces though they are not before the eyes and the wearer must solely rely on 20 the feeling of the hand, thereby reducing or removing the danger of the ring slipping away from under the fingers.

Fig. 1 of the drawing is an elevation of a connecting ring held between two fingers 25 ready to be applied to a hook, the fingers being shown in section.

Fig. 2 is an end view of a ring also held by thumb and finger of a hand, which itself is shown in elevation, and

Figs. 3 and 4 are similar views as Figure 1 30 of modified forms of a link.

The link or ring *a* fastened to the end of a belt *b* in usual manner, for instance a nape belt of a breathing mask, is gripped by the fingers *e* as shown in Fig. 2 when it is to be 35 slipped on the hook *c*. To secure the grip and prevent the link *a* from slipping away through the fingers it is roughened or knurled, as shown in Figs. 1 to 3, or provided with teeth or serrations *d*, as shown in Fig. 4. 40 This ensures a decided grip and hold, and slipping off need no more be feared.

The link instead of being circular may be given any suitable shape, for instance oval, as is shown in Fig. 3, which itself renders 45 slipping off more difficult.

I claim:—

A connecting ring for the belt of a breathing appliance having serrations on its outer periphery, the spaces between said serrations 50 being of sufficient width to enable a substantial portion of the width of the finger of the wearer of the breathing appliance to project between adjacent serrations when the ring is grasped by the fingers of the wearer. 55

In testimony whereof I have signed my name to this specification.

HERMANN STELZNER.
